[57] CLAIM

The ornamental design for a locomotive brake console, as shown.

DESCRIPTION

FIG. 1 is a perspective view of a locomotive brake console showing our new design;

FIG. 2 is a top plan view thereof rotated 90 degrees counter clockwise from the view of FIG. 1;

FIG. 3 is a front elevation view of FIG. 2;

FIG. 4 is a left side elevation view of FIG. 2;

FIG. 5 is a bottom plan view of FIG. 2;

FIG. 6 is a right side elevation view of FIG. 2; and

FIG. 7 is a rear elevation view of FIG. 2.
